COKE-OVEN APPARATUS

Joseph van Ackeren, O'Hara Township, Allegheny County, Pa., assignor to The Koppers Company of Delaware, a corporation of Delaware

Application January 15, 1931, Serial No. 508,915

4 Claims. (Cl. 202—248)

My invention relates to coke-oven apparatus and particularly to frames for coke-oven doors.

My invention is particularly applicable to frames for the doors of coke ovens of the horizontal type and is especially adapted for use in connection with doors of the self-sealing type.

In the production of frames for coke-oven doors, it has been the practice heretofore to construct the frames in a single piece comprising a plate portion for engaging the side wall of the battery and a flange portion for projecting within the end of the coke-oven door opening. The frame has been of cast iron and the large casting that is required has been difficult to construct and expensive because of its size.

Castings of this character have been difficult to maintain in proper working order because of their tendency to warp in use. This condition has resulted from the fact that the inner flange has been subjected to materially higher temperatures than the outer portion which is cooled by contact with the atmosphere. This unequal heating has expanded the flange within the door and caused the warping of the outer or plate portion. When these frames have been used for self-sealing doors of the type in which an outer flange portion has been adapted to engage a metal knife-edge portion such as is employed in the Wolff self-sealing door (British Patent 314,281 and United States Patent 1,908,467), the warping of the frame has seriously interfered with the successful operation of the sealing means.

It has been proposed heretofore to construct the frame of alloys of metal that are highly resistant to warping strains and that maintain the alignment of the frames to a higher degree than in the case of cast iron. Such frames have, however, been very expensive by reason of the nature of the material employed.

40 In accordance with the present invention, I provide a frame for use in connection with self-sealing doors that is so constructed as to maintain its alignment. The frame is constructed of an outer portion or plate member for engaging the side wall of the battery around the opening of the oven door. The inner portion, which corresponds to the flange of the usual oven door, comprises a plurality of relatively short sections, each of which is detachably secured to the outer plate member. These sections may be independently removed or replaced.

This arrangement insures that the frame will maintain its alignment by reason of the fact that the higher temperatures to which the interior sections are subjected will not cause strains that

tend to warp the outer member, since these sections are not integral with each other or with the plate member. Furthermore, since the inner sections may be independently replaced without disturbing the outer structure, the door frame 60 may be kept in repair at much lower expense.

The details of my invention will be described in connection with the accompanying drawings, in which

Figure 1 is a view in transverse vertical section of a portion of a coke-oven battery;

Fig. 2 is an enlarged horizontal sectional view of a portion of a coke-oven battery and an associated door frame taken on line 2—2 of Fig. 4;

Fig. 3 is a front elevational view of a door 70 frame constructed in accordance with my invention; and

Fig. 4 is a rear elevational view of the door frame.

Referring particularly to Fig. 1, a coke-oven 75 battery 1, only a portion of which is shown, comprises a series of oven chambers 2, only one of which appears in the drawings, a top 3, an ascension pipe 4 and a collecting main 5. The battery is also provided with the usual regenerators 80 6, one of which is shown, a producer gas main 7 and a coke-oven gas main 8.

Each coke-oven chamber 2 is provided with a removable door 9 that is positioned within a frame 10, to close the doorway to the coking 85 chambers, the details of which are shown in Figs. 2, 3 and 4.

Each door frame 10, which is adapted for use in connection with self-sealing doors of the Wolff type (British Patent 314,281), comprises 90 a substantially single-piece metallic door-frame or outer plate member 12, which engages the outer surface of the side wall 13 of the battery and extends continuously around the border of the door opening and door body, as shown in Figs. 95 2 and 3. The member 12 is held in position to retain the side walls of the battery by buckstays 14, which are in the form of channel members and are arranged in pairs, each pair being disposed between adjacent ovens. The inner edge of the 100 plate member 12 is provided with an outwardly-extending flange 15 for a purpose to be later described.

The inner portion of the door frame comprises an inner lining 16' constituted of a series of relatively short sections 16 that are angular in cross-section, as best appears in Fig. 2. One flange 17 extends parallel with the opening of the oven, while the other flange 18 extends parallel with the plate member 12 and is adapted to be detachably 110

secured to the latter by means of bolts 19. The sections 16 are placed end-to-end throughout the vertical height of the end opening of the oven chamber.

- 5 When the sections 16 are in position, a slot 20 in substantially the middle portion of its outer flange 18 is in alinement with an aperture or passageway 21 through the plate member 12. Through these alined openings or passageways, 10 a mixture of fire clay and sand mortar is introduced to provide an insulating or cementitious material, indicated at 22, between the plate member 12 and the refractory material of the battery wall.
- 15 Asbestos rope 23 is preferably inserted between the inner edge of the flange 17 in order to insulate the latter from the relatively high temperature of the oven wall. Any suitable material, such as rock wool 24, may be inserted in the 20 spaces between the edges of the adjoining plate members 12.

The door opening is closed by a door body indicated generally by the reference numeral 26 of the Wolff self-sealing type aforesaid which 25 comprises a framework 27 for engaging the projecting edges of the sections 16. The door is also provided with a member 28 having outwardly projecting flanges 29, each of which is provided with a spring plate member or elastic sealing 30 plate 30 for pressing a metal strip 31 having a substantially knife edge 31' into firm engagement with the outwardly-projecting flange 15 of the frame 12. The surface 15' of the flange 15 constitutes an abutting sealing surface and the knife 35 edge 31' constitutes the sealing edge of the metallic sealing members for forming an edged and abutting sealing engagement between them.

In the operation of the battery, the sections 16 become more highly heated than the plate 40 member 12, but the strains due to expansion within the sections are not transmitted to the plate member 12. The plate members 12, by reason of their contact with the atmosphere, remain relatively cool and there is, therefore, little 45 tendency for them to warp.

In view of the difference in conditions to which 50 they are subjected, the sections 16 have a short life relatively to that of the plate member 12 and it is, accordingly, necessary to replace them much oftener. In the construction of the prior art, it 55 was necessary to remove the buckstays in order that the integral frame might be removed and replaced because of defective portions in the door opening.

55 In the door frame of my invention, however, it is only necessary to remove the bolts 19 from the defective sections 16 and the latter may be removed and replaced with new sections. All of this may be accomplished without disturbing 60 either the buckstays or the plate member 12. The advantages of an arrangement that will permit the replacement of defective sections without disturbing the buckstays or the outer portion of the door frame will be appreciated by those familiar 65 with the difficulties that have attended the replacement of door frames of the prior art.

Furthermore, the separation of the door frame into several parts insures that the flange members 15 will maintain their alinement whereby 70 they may effectively co-operate with the sealing means on the door to retain the gases of distillation within the oven chamber.

The separation of the door frame into its parts permits the plate member to be made of relatively 75 inexpensive cast iron because it is not subject to

the strains that were present in an integral structure. Also, in view of the fact that the inner sections may be easily replaced individually, they may be made of ordinary cast iron because it is not necessary that they have the long life that is desirable for the outer portion of the frame. 80

The foregoing and other advantages will be appreciated by those skilled in the art of construction and operation of coke-oven batteries.

I claim as my invention:

1. In a coke oven apparatus, a coke oven door-body; a stationary coke oven door-frame therefor comprising a substantially single-piece metallic door-frame plate extending continuously around the border of said door-body; metallic sealing members between the door-body and the door-frame, said sealing members including an abutting sealing surface and an elastic sealing plate having an edged and abutting sealing engagement, the abutting sealing surface being stationary on the outer surface of said door-frame plate and the elastic sealing plate being carried by the door-body; and an inner lining on the inner surface of the door-frame plate comprising individual metallic sections, separate from each other and from the door-frame plate, arranged adjacent each other and so as to form an interposed heat protective lining on the inner surface of the edge portion of the door-frame plate adjacent the door interposed between the coking 100 chamber and the door frame.

2. In a coke oven, a coking chamber; an enclosing wall therefor having a coke oven door opening into said chamber; a stationary coke oven door-frame extending continuously around the 110 border of said door opening; a coke oven door-body for said door-frame; metallic sealing members between the door-body and the door-frame, said sealing members including an abutting sealing surface and an elastic sealing plate having an 115 edged and abutting sealing engagement, the abutting sealing surface being stationary on the outer surface of said door-frame plate and the elastic sealing plate being carried by the door-body; said door-frame comprising a substantially 120 single-piece metallic plate extending continuously around the border of said door opening; and an inner lining of individual metallic sections 125 extending into the door opening at an angle to the metallic plate, the metallic sections being separate from each other and from the metallic plate and arranged adjacent each other so as to form an interposed heat protective lining on the inner surface of the edge portion of the metallic plate adjacent the door opening interposed between the coking chamber and the door frame.

3. In a coke oven a coking chamber; an enclosing wall therefor having a coke oven door opening into said chamber; a stationary coke oven door-frame extending continuously around the border of said door opening; a coke oven door-body for said door-frame; metallic sealing members between the door-body and the door-frame, said sealing members including an abutting sealing surface and an elastic sealing plate having an 135 edged and abutting sealing engagement, the abutting sealing surface being stationary on the outer surface of said door-frame plate and the elastic sealing plate being carried by the door-body; said door-frame comprising a substantially single-piece metallic plate extending continuously around the border of said door opening; and an inner lining of individual metallic sections 140 extending into the door opening at an angle to the metallic plate, the metallic sections being 145 separate from each other and from the metallic plate and arranged adjacent each other so as to form an interposed heat protective lining on the inner surface of the edge portion of the metallic plate adjacent the door opening interposed between the coking chamber and the door frame.

rate from each other and from the metallic plate and arranged adjacent each other so as to form an interposed heat protective lining on the inner surface of the edge portion of the metallic plate 5 adjacent the door opening interposed between the coking chamber and the door frame; and buck stays for retaining said door-frame in position relative to the door.

4. In a coke oven, a coking chamber; an enclosing wall therefor having a coke oven doorway into said chamber; a stationary coke oven door-frame extending continuously around the border of said doorway; a coke oven door-body for said door-frame; metallic sealing members between 10 the door-body and the door-frame, said sealing members including an abutting sealing surface and an elastic sealing plate having an edged and abutting sealing engagement, the abutting sealing surface being stationary on the outer surface 15 of said door-frame plate and the elastic sealing

plate being carried by the door-body; said door-frame comprising a substantially single-piece metallic plate extending continuously around the border of said doorway; and on inner lining of individual metallic sections extending into the doorway at an angle to the metallic plate, the metallic sections being separate from each other and from the metallic plate and arranged adjacent each other so as to form an interposed heat protective lining on the inner surface of the edge portion of the metallic plate adjacent the doorway interposed between the coking chamber and the door frame; said individual sections and said metallic plate having passageways in alignment for introduction of packing material between the coking chamber enclosing wall and the door frame; and a packing of insulating material between the enclosing wall of the coking chamber wall and the door-frame.
